UNITED STATES PATENT OFFICE

WALTER JOHN BROWN, OF STOCKPORT, AND CECIL REGINALD BURCH, OF STRETFORD, MANCHESTER, ENGLAND, ASSIGNEES TO ASSOCIATED ELECTRICAL INDUSTRIES LIMITED, A COMPANY OF GREAT BRITAIN

RECEIVER FOR HIGH-FREQUENCY ELECTRIC SIGNALS

Application filed March 31, 1926, Serial No. 98,757, and in Great Britain March 31, 1925.

This invention relates to receiving apparatus for high frequency electric signals of the type in which a thermionic valve with associated circuits is arranged to be set into self-maintained oscillation by an incoming signal, and in which means are provided periodically to stop or quench such self-maintained oscillations.

Receivers of this type may be divided into two kinds, both of which kinds fall within the scope of the present invention.

In the first kind of receiver, the apparatus is tripped by an incoming signal from a stable non-oscillatory condition to a stable oscillatory condition, so that the strength of the self-maintained oscillations is independent of the strength of the incoming signal but dependent upon the characteristics of the valve and the constants of the associated circuits. Receivers of this kind will hereinafter be referred to as periodic trigger receiver.

In receivers of the second kind the thermionic valve and its associated circuits are caused to assume successively and alternately two states; one state is highly unstable, and during this unstable state free oscillations are initiated by an incoming signal their initial amplitude being proportional to the signal strength and their rate of increase being determined by the characteristics of the valves and the constants of the associated circuits. The other state is completely stable and in this state oscillations initiated in the first state die out to substantially zero amplitude. Receivers of this second kind will be hereinafter referred to as super-regenerative receivers.

According to the invention in a receiver of the type set forth the thermionic valve which is associated with circuits so arranged as to be set into self-maintained oscillation, has its anode circuit supplied with energy from a source of alternating electromotive force only.

In one form of receiver the alternating electromotive force is supplied by a local oscillator system such as an oscillator comprising a thermionic valve. For a super-regenerative receiver it is desirable that the frequency of the alternating electromotive force should

be high, preferably above or near the limit of audible frequencies, and in any case higher than any frequency with which the high frequency signal which is to be received, is modulated. For a periodic trigger receiver the frequency of the electromotive force may be much lower, for example fifty cycles per second.

An important feature of the invention consists in means to apply to the grid of the valve an alternating bias substantially proportional to and in phase opposed to the alternating electromotive force applied to the anode. This alternating bias should have a value substantially equal to the alternating electromotive force applied to the anode divided by the voltage factor of the valve. Since when an alternating bias of this value is applied to the grid of a valve the lumped voltage over the valve is reduced to zero, it is necessary to apply to the grid of the valve also a definite steady positive bias.

In order that the invention may readily be understood four embodiments thereof will now be described by way of example with reference to the accompanying drawings in which Fig. 1 represents diagrammatically a simple form of periodic trigger receiver of which the anode circuit is supplied directly from an alternator; Fig. 2 shows diagrammatically a periodic trigger receiver wherein means is provided to apply an alternating bias to the grid of the valve; Fig. 3 represents diagrammatically a super regenerative receiver wherein the anode circuit is supplied from a source of alternating electromotive force which comprises a three electrode valve; and Fig. 4 represents a modification of super-regenerative receiver in which means is provided to apply an alternating bias to the grid of the valve.

Like reference numerals indicate like parts wherever applicable in each of the several figures of the drawings.

In each of the several figures of the drawings batteries and circuits for heating the cathode or cathodes of the valve or valves are omitted for the sake of clearness and simplicity.

Referring now to Fig. 1 the grid 11 of the

thermionic valve is connected to the upper end of a closed oscillatory circuit formed by the inductance 15 and condenser 16. The lower end of the closed oscillatory circuit is connected to the cathode 13 through a by-pass condenser 17 and also adjustably to a potential divider 18. The potential divider 18 is connected across a battery 19 and the positive end of the battery 19 is connected to the cathode 13. The cathode 13 is connected to one terminal of an alternating current generator 20 of which the other terminal is connected through a relay 21 shunted by a by-pass condenser 22 and through a reaction coil 23 to the anode of the valve.

In operation the coupling between the reaction coil 23 and the grid circuit inductance 15 and the value of steady potential applied to the grid 11 are adjusted so that the arrangement has two stable states, namely, the first state in which the system does not maintain oscillations and a second state in which the system when once tripped into oscillation maintains oscillations of amplitude determined solely by the characteristics of the valve and constants of the circuits.

It will be appreciated that such oscillations can only be maintained during that half cycle of the generator 20 during which the anode 12 is positively electrified with respect to the cathode 13. Signals may be introduced into the grid circuit by coupling the inductance 15 to an aerial or by constructing part of the inductance 15 as a frame or loop aerial or by any other known method. Upon receipt of a signal the system is tripped into oscillation during that half cycle of the generator 20 which electrifies the anode 12 positively with respect to the cathode 13. The oscillations are quenched during that half cycle wherein the anode 12 is negatively electrified with respect to the cathode 13. If the signal still persists the valve or the system is again tripped into oscillation when the anode reaches a certain definite positive potential with respect to the cathode 13.

The valve in the above described adjustment is working about a point upon the lower bend of its anode-current grid-voltage characteristic and consequently when the system is in a state of oscillation the mean anode current of the valve will exceed by a considerable amount the mean anode current which flows when the system is not in a state of oscillation. The relay 21 is, therefore, so adjusted that it is not operated by the normal anode current of the valve but is operated by the mean anode current of the valve when the system is in a state of self-maintained oscillation.

The arrangement shown in Fig. 2 is broadly similar to that illustrated in Fig. 1. In this arrangement however means are provided to ensure that the potential of the grid 11 shall have a definite relation to that of

the anode 12. The generator 20 is connected through a transformer 25 to the ends of a potential divider 26. One end of the potential divider 26 is connected to that end of the potential divider 18 which is connected to the negative pole of the battery 19. The other end of the potential divider 26 is connected to the relay 21. The cathode 13 instead of being connected directly to the generator as illustrated in Fig. 1 is connected to a sliding contact upon the potential divider 26. The position of this sliding contact is adjusted so that the alternating voltage applied to the grid is substantially equal to that applied to the anode divided by the voltage factor of the valve. In these circumstances if the battery 19 and potential divider 18 were omitted the lumped voltage over the valve would be zero throughout the cycle of the generator 20; consequently it is necessary to provide, by means of the battery 19 and potential divider 18, a sufficient positive bias to the grid 11 to bring the system to the operative condition described in connection with Fig. 1.

It has been found that the voltage of the alternating supply means which may be used in place of the generator 20 may fluctuate from time to time to such an extent as to vary very considerably the sensitivity of the receiver shown in Fig. 1. If the tripping of the valve is so adjusted that it does not oscillate when normal voltage is applied to the anode but so that a very small signal applied to the grid will trip it into oscillation, then it is found that a slight increase in the voltage of the mains or generator 20 will cause the valve to trip even in the absence of a signal. Consequently, reliable working can only be achieved by adjusting the receiver illustrated in Fig. 1 so that a comparatively strong signal is required to trip the valve. It has been found that by adopting the arrangement illustrated in Fig. 2 the sensitivity of the receiver can be made substantially independent of the voltage amplitude applied to the anode over a wide range of amplitudes.

Referring now to Fig. 3 which illustrates a simple form of super-regenerative receiver the grid 11 of a valve is connected through a closed oscillatory circuit consisting of the inductance 15 and variable condenser 16 and through a by-pass condenser 17 to the cathode 13. The by-pass condenser 17 is shunted by a battery 19 of which the number of cells is adjustable so as to bias the grid 11 appropriately. The anode 12 is connected, through a reaction coil 23, through telephones 30, shunted by by-pass condenser 22, to one end of a closed oscillatory circuit formed by the inductance 31 and condenser 32, the other end of which is connected to a common lead joining the cathode 13 and the cathode 33 of a second valve. The upper end of the closed oscillatory circuit 31, 32 is also connected,

through a high tension battery or other source of direct electromotive force 34 shunted by a condenser 35, to the anode 36 of the second valve. The grid 37 of the second valve is connected, through a grid condenser 38, shunted by a high resistance 39, and through a reaction coil 40, to the conductor joining the cathodes 13 and 33. The reaction coil 40 is coupled to the inductance 31 so that oscillations are maintained in the circuit 31, 32. It will thus be seen that an alternating electromotive force only is applied to the anode circuit of the first valve. The frequency of the alternating electromotive force 15 may be adjusted by varying the value of the inductance 31 or condenser 32 or by varying both of these values. The frequency should be higher than the frequency of modulation of any high frequency signal which it is desired to receive and preferably should be near to or above the limit of audibility.

In operation, the coupling between the inductance 23 and the inductance 15 and the value of steady potential applied to the grid 25 11 by the battery 19 is so adjusted that when oscillations are initiated by a signal in the closed oscillatory circuit 15, 16 their amplitude is proportional to the amplitude of the signal and so that the rate of increase of 30 amplitude of the oscillations is constant. When oscillations are initiated in the circuit 15, 16 during that time the anode 12 is positively electrified in respect to the cathode 13, such oscillations will build up in amplitude 35 to a value which is proportional to their initial value and will be finally quenched by the positive potential of the anode 12 in respect to the cathode 13 falling to a definite amount. If the frequency of oscillations 40 maintained in the circuit 31, 32 is sufficiently high, telephonically modulated signals may be properly reproduced in the telephones 30.

Fig. 4 illustrates a modification of the kind of super-regeneration receiver shown 45 in Fig. 3 in which means is provided to cause the potential of the grid 11 to bear a definite relationship to the potential of the anode 12.

The junction of the closed oscillatory circuit 15, 16 and the by-pass condenser 17 is 50 connected to an adjustable contact upon a potential divider 18 which is connected across a battery 19. The negative end of the battery 19 is adjustably connected to a point of the inductance 31. The lower end of the 55 inductance 31 is connected to the grid 37 of the second valve and an intermediate point of inductance 31 is connected to the conductor joining the cathodes 13 and 33. The upper end of the inductance 31 is connected to the telephones 30 and through a blocking condenser 42 to the anode 36 of the second valve. The anode 36 of the second valve is connected 60 through a choke coil 41 to the positive pole of the battery 34 which is shunted by con-

denser 35. The negative end of the battery 34 is connected to the cathodes 33.

The position of the adjustable connection from the battery 19 to the inductance 31 is so adjusted that the alternating voltage applied to the grid 11 is equal to and opposite in phase to that applied to the anode 12 divided by the voltage factor of the valve. In these circumstances it is necessary that the potential divider 18 be so adjusted that steady positive bias is applied to the grid 11 in addition to the alternating bias so that the lumped voltage over the valve is not zero. By this means it has been found that the sensitivity of the receiver is substantially independent of variations in the strength of oscillations generated in the circuit 31 and 32 of the second valve due for example to variations in the voltage of the battery 34.

It will be appreciated that, while four embodiments of the invention have been described by way of example the invention is by no means limited to these four embodiments, and many modifications may be made without departing from the scope of the invention.

We claim as our invention:—

1. In radio receiving apparatus wherein oscillations may be generated, a thermionic device having a grid and plate, means for providing only alternating potentials on said plate, whereby oscillations in said apparatus will be quenched during negative-potential cycles independently of grid potentials in said thermionic device, and means for biasing said grid to a value insufficient to maintain oscillations during periods of non-reception.

2. In a radio receiving apparatus wherein oscillations may be generated, a thermionic device having a grid and a plate, means for providing only alternating potentials on said plate, means for biasing said grid to a value insufficient to maintain oscillations during periods of non-reception but sufficient, when affected by incoming signals, to maintain oscillations during positive cycles of the plate potential, and means for providing alternating potential on said grid bearing such relationship to the plate potential, whereby plate current characteristics will be maintained substantially uniform.

3. In radio receiving apparatus wherein oscillations may be generated, a thermionic device having a grid and a plate, means for providing only alternating potentials on said plate, means for biasing said grid to render said device incapable of oscillating during periods of non-reception of signal energy, means for providing an alternating potential on said grid in reverse-phase relationship to said plate potential and of a value equal to said plate potential divided by the voltage amplification factor of the device, whereby plate current characteristics will be maintained substantially uniform.

4. In radio receiving apparatus wherein oscillations may be generated, a thermionic device having a grid and a plate, means for providing intermittent positive potentials on said plate, means for providing biasing potential on said grid, said biasing potential having an alternating and a direct component, the negative cycles of the alternating component occurring simultaneously with the positive potentials on the plate, said negative cycles having a value substantially equal to the plate potential divided by the voltage amplification of said thermionic device, said direct component of the grid biasing potential being sufficient to render said device incapable of oscillating only during non-reception periods.

In testimony whereof we have hereunto subscribed our names this tenth day of March, 20 1926.
